UNITED STATES PATENT OFFICE.

HENRY J. BLEAKING, OF HERKIMER, NEW YORK.

PROCESS OF MAKING DRAWER-PULLS AND SIMILAR ARTICLES.

No. 919,815.

Specification of Letters Patent.

Patented April 27, 1909.

Application filed March 20, 1907. Serial No. 363,491.

To all whom it may concern:

Be it known that I, HENRY J. BLEAKING, a citizen of the United States, residing at Herkimer, in the county of Herkimer and State of New York, have invented certain new and useful Improvements in Processes of Making Drawer-Pulls and Similar Articles, of which the following is a specification, reference being had therein to the accompanying drawing.

My invention relates to an improved process of making drawer pulls and similar articles, and I declare that the following is a full, clear, concise and exact description thereof sufficient to enable one skilled in the art to make and use the same, reference being had to the accompanying drawings in which like letters refer to like parts throughout.

The invention includes the production of a drawer-pull made of a plurality of laminæ or sheets of wood united into an article of a given form of utility or of beauty, each sheet of which is separately brought to the general contour of the finished article, certain of them being given particular modifications of form for ornamental effects as desired and being severally of such material, grain and disposition as to form a new and useful article.

In the drawings Figure 1 is a front view of a drawer with one of my handles thereon; Fig. 2 is a perspective view of a handle of a different form and illustrating the ornamentation thereof; Fig. 3 is a view of a pin which I use in mounting the pull on the drawer; Fig. 4 is a top view of a handle, shaped to fit a drawer of curved front, the laminæ or sheets being broken away at each end, and Fig. 5 is a face view of a pull with the laminæ being broken away at the ends illustrating the variance in the grain of the laminæ.

Referring to the drawings in detail A indicates the drawer-end of desired size, form and shape, and B represents the handle, having ends *b* and the intermediate grip *c*. As already indicated the handle is made up of a series of sheets or laminæ of suitable material, *d*, held together in their assembled form by glue or other suitable means, combining them in a unit. These sheets are of a size slightly larger than that of the finished article and of a suitable thickness according to the nature of the material and its pliability. They may be of different kinds of wood if de-

sired, the inner ones, for instance, being of a cheaper grade and the outer one of a wood that will take on a desirable finish, the sheets being stained, if desired to correspond with the finish of the product. The different sheets may also be cut so that the grain of each will be more or less crosswise of that of the adjacent sheets, thereby securing strength in the pull. The arrangement in different grains and qualities is illustrated in Fig. 5.

The sheets or laminæ are prepared for assembling by soaking or steaming them. Each is then preferably shaped, by a suitable mold or press, into the form necessary for the finished product and they are then assembled under pressure with glue therebetween, if such be the means of uniting them.

In the process of producing the drawer-pull or similar article it is necessary to give only the outer lamina or sheet the dull and detailed configuration or ornamentation, the others being shaped to conform more or less closely to the design. The outermost one may be made thinner than the others and of a choicer material. The inner ones can be made of inferior wood or material, and be made thicker since it is not necessary that it should be pressed into a form to show all the details of the ornamentation. It is desirable that the innermost of the sheets should be substantially smooth or plane and this is effected by making each less close in detail to the figure of the outermost one. The interstices or spaces thus caused between the several laminæ are filled, more or less, by the glue or cement which unites the parts into a unit, giving solidity to the product. It will be understood, however, that at the edges each lamina preferably contacts quite closely with the edge of the contiguous one.

By suitable pressure the several laminæ, when properly prepared may be placed side by side in a press and brought to the desired form and then be allowed to dry. This method may be preferable under certain conditions, especially for plain work. It may be desired, however, that the pull shall present a more or less ornamental form. Such ornamentation is illustrated by *e* in Fig. 2. This is produced, as above set forth, by forming the outermost sheet in a press or die having the figure or such ornamentation. The extent of this is limited by the capacity of the wood to conform to such figures, depending upon its quality and cut. The outer

sheet may be cut or trimmed if desired, to have such ornamentation as desired. While different sheets might be similarly formed to produce a similar variation from a plane face 5 it is not necessary to do this. The outer sheet may be given the desired shape and the inner ones crowded against it in the assembling when, if sufficient glue be provided the interior cavities of the ornamentation will be 10 filled or they may be separately filled, before the assembling, by any suitable material.

It will be evident that the drawer pull can be given such shape or figure as is desired and can be made with its ends to conform to 15 the article to which it is to be attached, such as a curved surface and as indicated in Fig. 4.

After the laminae have been assembled in the unit and dried the pull is trimmed and finished as desired. It may be secured by 20 any suitable means to the drawer, or other article, but on account of its thinness I prefer to use a wooden pin f with head f' . The pull and drawer are bored and the pin inserted, held by glue or otherwise.

25 Having described my invention, what I claim as new and desire to secure by Letters Patent, is:

1. The process of making a laminated article consisting of a series of thin laminae 30 severally pressed and formed and subsequently secured to interfit in a structural unit, the outer thereof being separately pressed to present variations of figure from the normal plane surface of the lamina, substantially as shown.

2. The process of making an article of

assembled layers having an ornamental face and composed of a plurality of laminae, by pressing each into form to be assembled in the finished article, the outer or face lamina having been previously separately pressed with configurations of the ornamentation desired, the several laminae being united with cement provided to unite them and to fill the space formed by the configurations of the 40 outer lamina. 45

3. The process of forming a composite article composed of a series of laminae, which consists in pressing the outer one into the form of a given ornamentation and pressing 50 the next inner laminae successively into a form more or less closely corresponding to the configuration of the next outer one and applying a cohesive filler to the said laminae when assembled and placed under pressure, 55 whereby to provide a solid backing for the ornamental lamina.

4. The process of making laminated articles consisting of a series of thin laminae severally pressed and formed and subsequently secured to interfit in a structural unit, the outer thereof being separately pressed to present a form of ornamental curvature and the inner ones being pressed into general conformity with the form of the 60 outer one, substantially as described.

In testimony whereof I affix my signature in presence of two witnesses.

HENRY J. BLEAKING.
